UNITED STATES PATENT OFFICE

160,570

LIQUID VAPORIZER

Julian H. Bair, Seattle, Wash.

Application July 15, 1949, Serial No. 3,919

Term of patent 14 years

(Cl. D83—1)

To all whom it may concern:

Be it known that Julian H. Bair, a citizen of the United States, residing at Seattle, Washington, has invented a new, original, and ornamental Design for a Liquid Vaporizer, of which the following is a specification, reference being had to the accompanying drawing, forming a part thereof, in which

Figure 1 is a slightly enlarged perspective view of a liquid vaporizer, showing my new design;

Figure 2 is a side elevation of the same; and

Figure 3 is a top plan view of the same.

I claim:

The ornamental design for a liquid vaporizer, as shown.

JULIAN H. BAIR.
